UNITED STATES PATENT OFFICE.

SAMUEL A. SPENCER, OF OKLAHOMA, OKLAHOMA.

SKYLIGHT-BAR.

1,283,583.

Specification of Letters Patent.

Patented Nov. 5, 1918.

Application filed February 16, 1918. Serial No. 217,558.

To all whom it may concern:

Be it known that I, SAMUEL A. SPENCER, a citizen of the United States, and a resident of Oklahoma, in the county of Oklahoma and State of Oklahoma, have invented 5 a certain new and useful Improvement in Skylight-Bars, of which the following is a specification.

One of the principal objects of my invention 10 contemplates the provision of an astragal or pane supporting bar, designed more particularly with reference to its use in connection with a skylight and the like, embodying improved features of construction and arrangement of parts for effecting a durable and efficient weatherproof joint 15 between the glass panes.

Another object of my present invention 20 is to provide means, in the nature of auxiliary gutters, forming a part of, and communicating with, the main gutter, for collecting the water of condensation, which gathers on the under sides of the panes, and delivering it to the main gutter, the auxiliary gutters being so constructed as to 25 perform the added function of supporting the rests for the glass panes.

A further object provides an improvement 30 in the means for mounting the clamping bolt in the nature of a clip fastener securely and adjustably mounted on the astragal, whereby the disadvantageous practice of punching holes in the main gutter for receiving the bolt, is done away with, 35 and whereby the bolts may be shifted to properly register with the openings provided in the weather cap.

Still another object of the invention is to 40 provide an improved device of the class described, which will be extremely simple, durable, efficient in operation, and inexpensive to manufacture.

With these and other objects in view which 45 will become apparent as the description proceeds, the invention resides in the construction, combination and arrangement of parts hereinafter more fully described and claimed and illustrated in the accompanying drawings, in which like characters of reference 50 indicate like parts throughout the several figures, of which—

Figure 1 is a top plan view of one embodiment of the invention,

Figs. 2 and 4 are sections on the lines 2—2 and 4—4 respectively of Fig. 1, 55

Fig. 3 is a partial perspective view showing the parts detached,

Fig. 5 is a similar view of the clamp,

Fig. 6 is a plan view of a modified construction, 60

Figs. 7 and 8 are sections on the lines 7—7 and 8—8, respectively, of Fig. 6,

Fig. 9 is a perspective view of the clamping bolt and clip, and

Fig. 10 is a sectional view illustrating 65 a modified form of gutter.

In carrying out my invention I provide an astragal or supporting bar including, among other elements, a substantially U-shaped gutter 5. This gutter, which may 70 be referred to as the main gutter, may be formed of a suitable length of channel iron having its upper edges bent inwardly toward each other and then upwardly into vertical position, to form auxiliary gutters. 75 The indent portions at 6 form the inwardly inclined floors of the auxiliary gutters, and the vertically arranged portions 7 form the inner walls of the auxiliary gutters. It may be here stated that the astragal may be made 80 in one continuous length, as shown in Figs. 6 to 8 inclusive of the drawings, or in cases where the panes of glass are arranged in tiers one above the other, or in stepped relation, the latter being the arrangement shown 85 in Figs. 1 to 4 of the drawings, the astragal may be made in sections. The sections are, however, identical in construction and it will therefore suffice to describe but one of the sections. 90

Arranged within the auxiliary gutters longitudinally thereof are the rests indicated at 8 for the panes of glass. These rests are preferably formed of tubes of suitable soft metal. The tubes 8 are supported against 95 lateral inward movement by the vertical walls 7 of the auxiliary gutters, and against lateral outward movement by the inclined floors 6 of those gutters, and it is thus seen that the auxiliary gutters retain the rests 100 in proper position without the requirement of extrinsic fastening devices. The adjacent edge portions of the glass panes 9 extend over the main gutter 5 and lie upon the rests 8 in the manner indicated. 105

Arranged upon the upper surface of the

glass panes and bridging the space which occurs between them, is a flat strip 10 of soft metal such as lead. This strip adjacent its lateral edges is crimped up over the lower edges of the sides 11 of a weather cap 12 as at 13, the extreme lateral portions of the soft metal sheet being bent over as at 14 and inclined downwardly and outwardly to bear against the upper surfaces of the panes of glass. This weather cap 12 may be of sheet metal, and if desired it may be made of such metal as to have a limited amount of resiliency.

When the weather cap is drawn downwardly by means of the clamps to be herein-after described, the soft metal sheet 10 will be firmly retained, throughout that portion of its width which lies against the glass panes, in close contact with the glass and the outer edge portions 14 of the strip will likewise be held tightly in engagement with the glass. Thus, an extremely efficient weather-proof seal will be provided between the sheets of glass so that rain water and dust will be effectively excluded. This downward drawing of the weather cap will, moreover firmly clamp the panes of glass in place.

The clamping or fastening means alluded to consists of spaced bolts 15, each including a shank formed integrally with or otherwise suitably connected at its lower end with a clip. The clip essentially comprises a plate 17 having its lateral portions turned downwardly as at 18 and bent outwardly as at 19, said turned down portions being of a height substantially equal to the distance between these inner auxiliary gutter walls. The downturned sides or portions 18 of the clip have fingers 20 stamped therefrom, and these fingers are offset outwardly from the portions 18 of the clip a distance substantially equal to the thickness of the inner walls of the auxiliary gutters. The clip, as shown in the drawings, is, in assembling the device, slipped onto the inner walls of the auxiliary gutters in such manner that the side portions 18 of the clip fit against the inner faces of these inner gutter walls, while the downturned foot portions 19 engage under the auxiliary gutters at the points where the walls 7 and floors 6 merge one in the other. The fingers 20 fit over the upper edges of the inner walls 7 in the position shown. The bolt extends upwardly in the space between the adjacent glass panes, and extends through an opening 22 provided in the metal strip 10 and through a registering opening 23 provided in the weather-cap 12. The upper protruding end of the bolt is threaded to receive a nut 24 whereby to tighten the portions of the device together. It will thus be seen that the bolt may, in assembling the device, be adjusted longitudinally of the astragal, to properly register with the openings in the strip 10 and cap 12 when the latter are put

in position. Furthermore, the practice of having to punch holes through the main gutter to receive the headed ends of the bolts is done away with, and thus a great saving of labor and time is accomplished. The clips 70 17 are preferably made of suitably heavy resilient metal, so that having been adjusted into the proper position in assembling the device, they will remain there against accidental displacement while the assembling 75 process continues. When the nut 24 is turned down upon the bolt, the cap 12 is drawn downwardly and at the same time an upward tension is exerted upon the auxiliary gutters, so that the metal strip 10 and the 80 rests 8 will simultaneously be drawn and clamped against the opposite faces of the glass panes.

It will be noted that at intervals the auxiliary gutters are notched or recessed as at 25, 85 and in this way communication is established between the auxiliary gutters and the main gutter, so that the water of condensation which forms on the under side of the glass panes, in draining into the auxiliary gutters, 90 may flow through these recesses or openings into the main gutter, the auxiliary gutters thus being prevented from overflowing. Furthermore, the openings serve as vents whereby warm air may circulate up and 95 through the astragal to the top or hip of the skylight (not shown), to be discharged through a ventilated ridge formed on the hip, whereby the air will be kept at a more even temperature adjacent the glass so that 100 excessive sweating or condensation of water will be prevented.

The upper and lower sections of the astragal may be conveniently termed A and B respectively. It will be noted that the upper end of the lower section B is provided with an upstanding tongue 26, formed by bending upwardly an extended portion of the floor of the main gutter. The section B rests adjacent its upper end against one of a plurality of purlins, of a construction commonly provided. This purlin is indicated at 105 27. In order to secure the end of the lower section against the purlin, there is provided a metallic clip or fastening device indicated 110 at 28, and consisting of a strip of metal having its ends, as at 29 and 30 respectively bent around the upstanding tongue 26 and the lower flange of the purlin 27. The lower end of the upper section A has the lower 115 portions of the side walls of the main gutter extended as at 31, and engaged between the side walls of main gutter of section B. The upper edges 32 of these extensions 31, fit in the angle formed at the junction of the side walls of the main gutter and the floors of the auxiliary gutters. The floor of the main gutter of section A rests upon the upper edge of the clip or fastener 28 as shown, and this floor is extended into the upper portion 120 125 130

of lower section B and is downturned to provide a tongue 33 which extends toward the floor of the main gutter of section B, and which effectually prevents the section

- 5 A becoming accidentally detached from the lower section. The upper section of the astragal is thus set up or stepped up from the lower section, and is locked at the junctions of the sections with the lower section against 10 accidental disengagement. It may here be noted that the ends of the weather caps 12 with which both sections of the astragal are equipped, are closed by suitable plates 34, so that no dust or water can enter the weather 15 caps. At the junction of the two sections of the astragal it will be noted that the upper end of the soft metal strip 10 is bent downwardly as at 35 and fits against the upper ends of the glass panes. The glass of the 20 upper section, it will be noted, extends down below the end of the upper section of the astragal and overlaps the upper portion of the lower panes of glass, resting upon the top of the upper portion of the lower 25 weather cap 12.

In the construction shown in Figs. 6 to 9 the astragal or supporting bar 40 is a U-shaped gutter, similar to the bar 5, and having the auxiliary gutters formed by the 30 walls 41 and 42, corresponding to the walls 6 and 7 of Figs. 1 to 4. The rests 43 are arranged within these gutters, and the sheets 44 of glass are laid on the rests.

The weather cap comprises a body 45 having at each side a substantially V-shaped gutter 46 and the outer wall of each gutter has a flange or extension 47, extending at an angle to the said wall. The weather caps are clamped on the glass in a manner to be 40 presently described, and a cord or cable 48 impregnated with tar is arranged in the angle between the outer wall 46 of each gutter and the adjacent flange 47 between the said angle and the adjacent sheet of glass.

45 The clips shown in Figs. 1 to 5 inclusive for holding the weather cap to the astragal as shown in Fig. 9, comprises a U-shaped member consisting of a body 49 and arms 50, and the body is provided at each end 50 with an extension 51, which are adapted to engage beneath the inturned portions of the astragal when the clip is in place. The arms 50 of the clips extend upwardly along the inner faces of the walls 42 of the gutter, 55 and each arm is provided at its upper end with an outwardly extending flange or rib 52 which engages over the edge of the adjacent wall 42.

The body of the clip is provided with an 60 upstanding stem between the arms, the said stem comprising a plain portion 53 and a threaded portion 54 and an annular shoulder is formed between the said portions. The plain portion of the stem is of a length 65 to cause the shoulder to engage the under

faces of the sheets of glass, and the stem passes up between the adjacent edges of the sheets and through an opening in the weather cap where the stem is engaged by a nut 55 to clamp the parts together.

In use, the weather cap is pressed down tightly on the tarred cords 48, compressing the said cords and making a tight seal between the glass and the weather cap. Any moisture that may fall upon the weather 70 cap will pass away along the gutters 46 or will be deflected outwardly by the flanges 47. Condensed moisture on the inner faces of the sheets will pass away by way of the gutters 41—42. The clip is held from upward movement by the extensions 51 and from downward movement by the ribs or flanges 52.

It will be understood that sheets of glass may be left as shown in Figs. 1 to 5 or they 85 may be arranged in the same plane as shown in Figs. 6 to 8. In the latter case a connecting plate is provided, comprising a substantially U-shaped body 56, which rests on the edge of the lower sheet of glass. A cord 57 impregnated with tar is arranged within the U-shaped body between the arms thereof and between the edge of the glass and the body.

The connecting plate is formed from a 95 strip bent to shape, and at one of the arms of the body the strip is bent backward upon the said arm as shown at 58 and is then bent downwardly at an angle to the portion 58 as shown at 59, and then is extended parallel 100 with the portion 58 but in offset relation as indicated at 60, and the free edge of the portion 60 is bent upward at an angle to the said portion as shown at 61. The relative proportion of the parts is such that, when 105 the sheets of glass are in place, the portion 60 will rest upon the connection between the gutter wall 41, and the body of the astragal with the free edge of the portion 61 engaging the under face of the next uppermost 110 sheet of glass.

A tarred cord or cable 62 is arranged in the gutter formed by the portions 59, 60 and 61 near the portion 59 and between the portions 60 and the under face of the glass 115 sheet. The cords 57—62 form a seal for preventing the entrance of moisture between adjacent sheets of glass, and when the nut 55 is turned down tightly, the cords are compressed. The upper arm of the body 56 120 of the connecting plate overlying as it does the upper face of the next lowermost sheet, deflects moisture out of the joint between the said sheets.

It will be observed from Fig. 10, illustrating a slightly modified form, that the particular shape of the upper edges of the gutters need not be strictly adhered to, and the vertical terminal edges 7 and 42, may be dispensed with. Thus, referring to Fig. 10, 125

the gutter 70 may have its upper edges 71 bent inwardly to support the rests 72 and slightly concaved as seen to form the auxiliary gutters, these edges having openings 5 which admit water of condensation into the gutter.

I claim:—

1. An astragal section comprising, a main gutter having its side walls at their upper portions bent inwardly at an inclination and then vertically upwardly to provide auxiliary gutters, tubular rests laid in the auxiliary gutters longitudinally thereof for supporting glass panes, a soft metal strip 10 adapted to be laid upon the upper surfaces of the sections of glass for bridging the space between said sections, a weather cap arranged upon the metal strip, said metal strip having its lateral edges crimped over 15 the edges of the weather strip, and a clamp means consisting of a bolt extending through the metal strip and weather cap and provided with means for tightening the latter, said bolt having a clip provided with 20 portions engaging the walls of the auxiliary gutters, substantially as described.

2. An astragal section consisting of a main gutter, auxiliary gutters formed on the main gutter and extending in spaced and 30 parallel relation with each other, rests arranged in the auxiliary gutters for supporting sections of glass, said auxiliary gutters having notches therein affording communication between the auxiliary gutters and the 35 main gutter, said auxiliary gutters having vertical inner walls and inwardly slanting floors engaging the said rests for retaining the latter in position.

3. In an astragal, the combination of a 40 main gutter, auxiliary gutters formed on the main gutter, and communicating with said main gutter, rests arranged within the auxiliary gutters for supporting glass panes, a weather cap, a soft metal strip carried 45 thereby for bridging the space between the glass sections, a clip slidably mounted upon the auxiliary gutters, a bolt carried by the clip and extending through registering openings in the weather cap and metal strip, 50 and means carried by the bolt whereby the cap and strip may be pressed against the glass sections on one side and the rests be pressed against the glass sections on the opposite side.

4. In an astragal, the combination of a 55 main gutter, auxiliary gutters carried thereby, rests carried by the auxiliary gutters for receiving panes of glass, a weather cap having a soft metal base for bridging the space 60 between the glass sections, a clip slidably mounted upon the auxiliary gutters, and means carried by the clip and engaging the weather cap whereby the panes of glass may be clamped between the soft metallic base 65 and the rests.

5. An astragal including a lower main gutter section having its floor at its upper end provided with an upstanding tongue, a clip engaging over the tongue and over one of the purlins for anchoring the upper end 70 of the lower section, said lower section having inwardly extending auxiliary gutters defining an angle between the floors of the gutters and the side walls of the main gutters, an upper main gutter section having 75 the lower portion of its side walls extended and arranged in the angle formed between the auxiliary gutters of the lower section on the main gutter of said lower section, said upper main gutter section being supported by said upstanding tongue, and a downturned tongue formed on the floor of the upper main gutter section, for preventing 80 accidental disengagement of the section.

6. An astragal, including a lower and an upper main gutter section arranged in stepped relation to each other, auxiliary gutters formed on the main gutter section, rests carried by the auxiliary gutters for supporting panes of glass, weather strips bridging the spaces between the glass panes, the upper panes of glass overlying the lower weather strip, and fastening means connected with the auxiliary gutters and with 90 the weather cap for clamping the latter against the glass panes.

7. An astragal including a lower and an upper main gutter section arranged in stepped relation to each other, glass panes 100 supported by the upper and lower sections, weather caps arranged on the panes to bridge the joint therebetween, means connecting the weather caps with the gutters for clamping said weather caps against the 105 glass panes, the lower cap being extended at its upper end and engaging upon the upper gutter section, and interlocking means between the gutter sections.

8. An astragal including a main gutter 110 having its side walls bent inwardly and upwardly to provide auxiliary gutters, said auxiliary gutters being notched whereby to establish communication between the auxiliary gutters and the main gutter, and between the main gutter and the outside atmosphere.

9. An astragal including sealing means comprising a strip of soft metal adapted to bridge the joint between adjacent panes, a 120 channel member over the edge portions of which the strip is crimped, said strip having its lateral portions extending outwardly at an angle and adapted to engage panes along lines spaced from the body portion of the 125 strip.

10. An astragal including a weather cap constructed to bridge the joint between adjacent panes, means adapted to be engaged by the cap for forming a seal between the 130

cap and panes, and means for drawing the cap toward the panes whereby to clamp the said cap engaged means against the panes.

11. An astragal including sealing means comprising weatherproof cords adapted to lie upon panes upon opposite sides of the joint occurring between the panes, a channel member having gutters and having flanges coacting with the adjacent walls of the gutters in engaging over the cords for

retaining them against the panes, and means for drawing the channel member toward the panes.

12. In a structure of the character described, a gutter having inwardly bent upper 15 side edges forming supports for glass rests, and apertured to admit moisture into the interior of the gutter.

SAMUEL A. SPENCER.
